Primary Examiner — Susan Moon Lee

(57) **CLAIM**

The ornamental design for a cat scat mat, as shown and described.

DESCRIPTION

FIG. 1 is a front, bottom perspective view of a cat scat mat, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of detail "9" identified in FIG. 1. The dash dot dash lines in FIGS. 1 and 9 are for the purpose of illustrating the enlarged view indicators and form no part of the claimed design.

1 Claim, 9 Drawing Sheets
